UNITED STATES PATENT OFFICE.

EUGENE G. DEUCHER, OF CLEVELAND, OHIO, ASSIGNOR TO THE UNIVERSAL CRANE COMPANY, OF ELYRIA, OHIO, A CORPORATION OF OHIO.

CRANE AND THE LIKE.

Application filed January 25, 1924. Serial No. 688,386.

This invention relates to cranes and similar devices in which a rotatable super-structure, including power operated raising and lowering mechanism, is movably mounted upon a conveyance.

It is well known that in cranes, power shovels and the like, the super-structure including power operated raising and lowering mechanism is mounted to be rotated in a single position upon the conveyance. It is also known that the rotatably mounted super-structures, of such devices, are sometimes mounted so that they can be moved upon a pair of tracks carried by a conveyance, thereby increasing their operating area when the conveyance is in any given position.

An object of my invention is to provide a device, of the character described, in which the super-structure is mounted so that it can be moved into substantially any position upon a conveyance, permitting the power operating raising and lowering mechanism to be operated in a maximum area when the conveyance is stationed in any given position.

Another object of my invention resides in mounting a rotatable super-structure upon a conveyance so that it can be moved to any desired operating position thereon by either longitudinal or transverse movement, or both.

Another object of my invention resides in the mechanism utilized for moving the rotatable super-structure transversely of the conveyance upon which it is mounted.

These and other objects will appear hereinafter, and an exemplification of one embodiment of my invention appears in the accompanying drawings in which:—

Fig. 1 is a side elevation of a power crane movably mounted upon a railroad car;

Fig. 2 is an end elevation of the same;

Fig. 3 is a plan view of the supporting frame for the super-structure, including the carrier base, and the mechanism for moving the same longitudinally and transversely, and

Fig. 4 is a fragmentary side elevational view partly in section showing the mechanism for driving the supporting frame longitudinally upon the railroad car.

Referring to the drawings by characters of reference, 10 represents a conveyance

which is herein illustrated as a flat bottom open railroad car. This car is of a conventional type, being mounted upon bolsters 11, to which are mounted axles 12 having supporting wheels 13 journaled thereto and adapted to roll upon railroad tracks 14. A pair of parallel rails are secured longitudinally upon the bottom, or floor, of the car and extend substantially the entire length thereof.

Upon the car, or similar conveyance, I mount a raising and lowering apparatus in such manner that it can be moved in a plurality of directions and is rotatable in any of such positions. I particularly desire that the movement of the apparatus should be such that it can be stationed in any position within the area of the floor of the car, thereby permitting a maximum working radius for the crane which is desirable for the many classes of work which can be performed.

The raising and lowering apparatus, which is herein illustrated as a power operated crane, is provided with a supporting frame which includes a pair of spaced axles 16 having wheels 17 journaled upon adjacent ends thereof, a side frame member 18, and a carrier base which is secured between the two axles. The side frame member is formed of an angle iron, and the reduced ends 9 of the axles extend therethrough and nuts 19 are threaded upon the reduced ends of the axles to rigidly secure the side frame member to the axles. A carrier base extends between the axles 16 and is formed of U-shaped side beams 20 and end beams 21, the end and side beams being rigidly secured together by angle brackets 22 which are secured thereto by rivets or other similar means.

A pair of transverse beams 8 are provided one adjacent and parallel to each end beam and are secured to the side beams 20 by angle brackets 22. The transverse beams 8 are further secured to the side beams 20 by gussets 7 secured upon the adjacent top surfaces thereof. The carrier base is slidably supported upon the axles 16 by yokes 23 which are apertured to receive the shaft, and the arms 6 of the yokes are secured to the ends of the side beams 20 by bolts 5. A base member is provided with a circular track 24 at its outer edge and is secured upon the transverse beams 8 and the side beams 20. The central portion of such

base provides a bearing upon which the gear 4 is rotatably mounted, such gear being positioned beneath the super-structure. The carrier base forms a part of the supporting frame and directly carries the super-structure of the power shovel which is mounted upon the circular track, the carrier base being movable lengthwise upon the axles on which it is mounted, and transversely relative to the railroad car.

The super-structure consists of a crane operating mechanism of conventional type which includes a frame 25 supported upon wheels 26 which are mounted to roll upon the circular track 24 of the supporting frame. The mechanism of the crane consists generally of a power plant 27 which operates gears 28 and 29 which are in mesh and which are connected to drums for respectively operating the pivoted boom 30 and the clam bucket 31.

A shaft 32 extends downwardly from the super-structure, and is rotated by a bevel gear 70 secured to one end thereof, such gear being rotated by a bevel gear 71 mounted upon the same shaft as gear 29. This shaft 32 is provided at its lower end with a spur gear 33 which is in mesh with the spur gear 4 mounted upon the base. The gear 4 is rotated upon the base and has bevel gear teeth 72 extending therefrom which mesh with a bevel gear 36 which is keyed to a drive shaft 34. This shaft is mounted to rotate in bearings 35 secured to beams 8 and 21 at one end of the carrier base. The outer end of this shaft is provided with a bevel gear 37 which meshes with a bevel gear 38 which is slidably keyed upon one of the axles 16 of the supporting frame. This last mentioned gear is formed in two parts which are provided at one end with flanges which engage the flanged end of a sleeve 74, and is clamped thereover by bolts 75. The sleeve 74 is formed as a part of the bearing 23, and the gear 38 will therefore move with the carrier base, thereby maintaining the gear 38 in mesh with the driving gear 37 in all positions of the carrier base. By means of the gearing and shafts described, the supporting frame can be longitudinally propelled by the engine upon the rails 15, the entire length of the car 10, or to any desired position intermediate the ends thereof, suitable means being provided to lock the frame to the tracks when in desired longitudinal operating position, and suitable clutch mechanism being provided to control the driving operation of the engine.

The carrier base is provided with threaded bearings 39 secured to and projecting through one of the side beams 20 and apertured brackets 40 are secured to the end members 21 with the apertures in alignment with the bearings. Threaded rods 41 are rotatably secured to the frame member 18

and extend through the threaded bearings 39 and apertured brackets 40. The threaded rods have sprockets 42 secured thereon and a chain 43 extends around the same, causing them to rotate simultaneously when one is operated. A shaft 44 extends through the frame member 18 adjacent to and parallel with one of the rods and is provided on its inner end with a sprocket 45 and on its outer end with a hand crank 46. A sprocket 47 is secured on one of the threaded rods, and a chain 48 extends around the sprockets 45 and 47. By turning the hand crank 46 the rods 41 can be rotated in either direction, causing the carrier base to be moved transversely upon the axles 16. The super-structure is rotatably mounted upon the carrier base, which base can be moved into substantially any position upon the car floor by means of the longitudinal and transverse movements above described, thereby providing a maximum working radius for the crane about the conveyance when it is in a desired position. It will also be seen that the super-structure can be positioned upon the car so that the clam bucket can operate at one side of the track without the super-structure extending into the path of trains which pass on the adjacent track, as illustrated in Fig. 2.

Various changes may be made in the details of the structure described without departing from the spirit of my invention and the scope of the claims.

What I claim is:

1. In combination with a railroad car having a pair of longitudinally extending tracks mounted thereon, a wheeled supporting frame mounted to travel upon the tracks on said car, said frame including a carrier base movable in another direction to that in which the frame is moved upon said tracks, a power operated super-structure rotatably secured upon said carrier frame, means driven from said super-structure for propelling said frame upon the tracks on said car, and mechanism for moving said carrier base relative to said supporting frame.

2. In an apparatus of the character described the combination of a conveyance having tracks mounted thereon; a super-structure including work performing mechanism; and a supporting frame for supporting said super-structure upon said conveyance, said frame including a pair of axles, wheels on said axles adapted to roll on said tracks, and a carrier base extending between and slidably mounted upon said axles.

3. In an apparatus of the character described, the combination of a conveyance; a super-structure including power operated work performing mechanism, and a supporting frame comprising a pair of axles, wheels journaled upon the ends of the axles for moving said frame upon said conveyance, and a carrier base having yokes slidably

mounted upon said axles, said base supporting said super-structure and being movable lengthwise of said axles.

4. In an apparatus of the character described, the combination of a conveyance; a supporting frame movable longitudinally upon said conveyance, said frame including a carrier base mounted therewith to be moved transversely of said conveyance; a super-structure rotatably secured upon said carrier base; and a pair of manually operated screw rods for moving said carrier base transversely relative to its supports.

5. In an apparatus of the character described, the combination of a conveyance, a supporting frame movable longitudinally upon said conveyance, said frame including

a carrier base mounted therewith to be moved transversely of said conveyance, and a super-structure rotatably secured upon said carrier base.

6. In an apparatus of the character described, the combination of a conveyance, a supporting frame movable longitudinally upon said conveyance, said frame including a carrier base mounted therewith to be moved transversely of said conveyance, and a super-structure rotatably secured upon said carrier base, and means for moving the carrier base transversely relative to its support.

In testimony whereof I have hereunto affixed my signature this 9th day of January 1924.

EUGENE G. DEUCHER.
